UNITED STATES PATENT OFFICE.

LOUIS WOJIDKOW, OF BROOKLYN, NEW YORK.

DESIGN FOR A TOASTER.

SPECIFICATION forming part of Design No. 26,437, dated December 22, 1896.

Application filed November 13, 1896. Serial No. 612,037. Term of patent 31 years.

To all whom it may concern:

Be it known that I, LOUIS WOJIDKOW, a citizen of the United States, residing at Brooklyn, in the county of Kings and State of New York, have invented and produced a new and original Design for Toasters, of which the following is a specification, reference being had to the accompanying drawings, in which—

Fig. 1 is a side view of the same. Fig. 2 is a view partly in section and partly in elevation.

The leading feature of my design consists of a circular beaded frame surrounding a wire-netting and a fanciful handle attached thereto by a scroll.

A represents a piece of wire-netting surrounded by the circular frame B, beaded or rounded, as shown at *a b*, Fig. 2.

C represents a fanciful handle secured to the frame B by means of the scroll D. 20

What I claim is—

The design for a toaster, as herein shown and described.

LOUIS WOJIDKOW.
